H. K. SWEENEY.
CULVERT.
FILED FEB. 25, 1922.

UNITED STATES PATENT OFFICE.

HARRY K. SWEENEY, OF ALCOVA, WYOMING.

CULVERT.

Application filed February 25, 1922. Serial No. 539,267.

To all whom it may concern:

Be it known that I, HARRY K. SWEENEY, a citizen of the United States of America, residing at Alcova, in the county of Natrona and State of Wyoming, have invented certain new and useful Improvements in Culverts; and I do hereby declare that the following is a full, clear, and concise description of the same, such as will enable others skilled in the art to which it appertains to make and use the same.

This invention relates to improvements in plastic culverts, having for an object to provide a culvert provided with a novel form of bottom or base, so constructed and arranged as will permit it to have the necessary adjustment with relation to the remainder of the culvert for compensating for any variance therein, such as expansion or contraction, by reason of the conditions to which the same may be subjected when in use, and also, to ensure of fluid tight connection between said base and the remainder of the culvert.

Other objects will be in part obvious and in part pointed out hereinafter.

In order that the invention and its mode of application may be readily understood by persons skilled in the art, I have in the accompanying illustrative drawings and in the detailed following description based thereon set forth several possible embodiments of the same.

In these drawings:

Figure 1 is a side elevation of my improved culvert with the sections thereof in assembled relation;

Figure 2 is a transverse section through the same taken on the line 2—2 of Figure 1 looking in the direction in which the arrows point;

Figure 3 is a detail in side elevation of one of the sections of the culvert;

Figure 4 is a fragmentary longitudinal section therethrough taken on the line 4—4 of Figure 1 looking in the direction in which the arrows point;

Figure 5 is a fragmentary perspective view of a slightly modified form of the culvert;

Figure 6 is a similar view of the opposite end of a modified form of culvert;

Figure 7 is a fragmentary side elevation of said modified form of the culvert and

Figure 8 is a detail transverse section through the lower portion of the same.

Having more particular reference to the drawings, in connection with which like characters of reference will designate corresponding parts throughout, my improved culvert comprises a plurality of sections generally indicated by the numeral 1, these sections being formed of plastic material, such as concrete or the like and being of a substantially cylindrical shape as shown in Figure 2. The lower portions of each of these sections 1 are open and adapted to receive therein bottom or base sections indicated at 2, said bottom sections being formed of material corresponding to that employed in construction of the body portions of the conduit sections 1 and having the upper portions of the opposite sides thereof beveled or flared outwardly as at 3, whereby to provide a substantially wedge like engagement as between the bottom sections 2 and the lower open portions of the culvert sections 1. In order that the various sections 1 can be secured in their longitudinally juxtaposed relation, shown in the Figure 1, laterally extending lips 4 are formed upon the upper portions of certain of the ends of each of the same and are adapted to be snugly engaged in seats formed in the adjacent end of the opposite section thus providing inter-connection as between the juxtaposed sections whereby with the arrangement of a binding material between the same, such as mortar or the like, the culvert sections will be securely locked. In this connection, it is of course to be understood that the adjacent ends of the various bottoms 2 abut each other and in this way, afford a fluid tight connection with the arrangement of suitable binding material between the same.

Through the connection of the lips 4 arranged upon certain of the ends of the conduit or culvert sections in their respective seats provided upon the adjacent ends of the corresponding sections, it will be understood that relative lateral movement between the conduit sections will be prevented. To prevent relative longitudinal movement between said sections and therefore, to retain their inter-engaging portions in snug relation at all times, I may and preferably do form upon the extremities of said lips 4, dove tail connections 4', which, as shown in the Figure 3 are adapted to be engaged in correspondingly formed seats cut or otherwise presented in the rear walls of

those seats in the ends of the adjacent section receiving the lips 4. By reason of this form of inter-engagement between the conduit or culvert sections, relative longitudinal movement between the same will be prevented as well as any undue lateral movement.

In the Figures 5, 6 and 7, I have shown a slightly modified form of my invention, 10 wherein the same is substantially square in cross section, consisting of body portion sections 5 having the lower portions of the side walls thereof formed with beveled seats 6 upon their inner faces and adapted to 15 snugly receive bottom or base sections 7, the opposite side portions of which are beveled or flattened outwardly as indicated at 8, thus providing a wedge like connection between 20 said sides of the bottom portions and the respective bases or bottom therefor.

In order that connection between the culvert body sections 5 may be effected, I may and preferably do form lateral extensions 9 upon certain of the ends of the same, 25 beveling their side walls as at 10 and engaging the same in seats formed upon the adjacent end portions of the juxtaposed body sections 5 as indicated at 11, these 30 seats being beveled to correspond to the beveling of the lateral extensions 9 indicated at 10. Thus, with assembly of the various culvert sections so that the same are arranged in juxtaposed longitudinal alignment, they will be positively inter-connected 35 and with the arrangement of a binding material, such as mortar or the like between the contacting portions thereof, a fluid tight connection between the culvert sections will be afforded.

40 Due to the wedge like seating of the bottom or base portions 2 and 7 in their respective culvert body sections, it will be understood that expansion or contraction of said body portions will be permitted with 45 relation to the bottoms or bases, which elements, by reason of their wedge like or adjustable engagement in the open portions of their respective culvert body portions will be permitted to automatically adjust 50 themselves to compensate for such expansion or contraction. Furthermore, by reason of the wedge like seating of these bottoms or bases in the lower open portions of the culvert sections, it will be understood 55 that fluid tight connection as between the same and their respective culvert sections will be afforded, thus allowing the culvert to be employed with maximum results.

As means for preventing relative longitudinal shifting or like movement between

the conduit or culvert sections, I may and preferably do form upon the extended ends of the several lips 9, dovetail-like extensions 9', the same as shown in the Figure 6, being located intermediate the opposite 65 sides of said lips or extensions and being adapted to snugly engage the correspondingly formed seats 12 arranged in the rearward walls of the portion 11 adapted to receive the extensions 9 therein.

Manifestly, the construction shown is capable of considerable modification and such modification as is within the scope of my claims, I consider within the spirit of my invention.

I claim:

1. A culvert comprising a plurality of longitudinally juxtaposed sections having their lower portions open and the side walls of said open portions being beveled to constitute seats, closures for said open lower portions of the sections engaged with the beveled portions thereof, longitudinally disposed lips upon certain of the ends of said sections adapted to have snug reception in correspondingly formed seats formed in the opposite ends of the sections whereby to inter-connect the same and to prevent relative lateral movement therebetween, and dove tailed extensions upon said first extension adapted to be snugly received in correspondingly formed seats formed in adjacent portions of the sections whereby to prevent relative longitudinal movement between the same.

2. A culvert comprising a plurality of longitudinally juxtaposed sections each being substantially rectangular in cross section and having their lower portions open forming a top and side walls, several seats formed with the lower end and projecting inwardly of said side walls, closures for said open lower portion of the sections, the opposite sides of said closures being beveled and adapted to adjustably engage the several seats, longitudinally disposed lips formed upon certain of the ends of said closure and top wall of said sections adapted to have snug reception in correspondingly formed seats formed in the opposite ends of the same whereby to inter-connect the same and to prevent relative lateral movement therebetween and means adapted to inter-connect said closures and top walls of said sections whereby to prevent relative longitudinal movement therebetween.

In witness whereof I have hereunto set my hand.

HARRY K. SWEENEY.
